DIAL PLATE

Filed June 14, 1947

Fig. 3

Inventor:
Nathan Pritikin
By: Henry Flech
Attorney

This is a continuation-in-part of my application for a patent filed on January 15, 1947, Serial No. 637,330, now abandoned, and for which a patent was issued on June 24, 1952, Serial No. 2,561,672.

UNITED STATES PATENT OFFICE

DIAL PLATE

Nathan Pritikin, Chicago, Ill.

Application June 14, 1947, Serial No. 754,730

4 Claims. (Cl. 41—22)

1

The invention relates to dials or signs and particularly to those adopted for edge lighting.

In standard practice dials, as for instance used for radios, are made of a glass plate on which the calibrations are indicated and a sheet metal backer is secured to the glass plate by integral lugs bent over the plate. The glass plate being painted with an opaque color on its face with the exception of portions through which the light penetrates, the metal backer must have like portion cut out in registry with the unpainted portions so that edge lighting may be used.

The provision of a metal backer and the forming of the cut out portions is quite expensive.

Attempts have been made to eliminate the backer and to merely apply an opaque color to the rear side of the dial plate. However, in such cases the dial plate does not lend itself to edge lighting.

It is, therefore, an object of the invention to provide a backer of transparent material and paint the backer with an opaque color, except the portions which coincide with the unpainted portions of the dial plate.

It is a further object to provide a transparent backer which is secured to the dial plate to obviate interference with the edge lighting.

With these and other objects in view which will become apparent from the disclosure of the invention, the latter comprises the means described in the following specification, particularly pointed out in the claims forming a part thereof, and illustrated in the accompanying drawing in which:

Fig. 1 is a front view of a known radio dial plate.

Fig. 2 is a section on the line 2—2 of Fig. 1.

Fig. 3 is a front view of the improved dial plate.

Fig. 4 is a section on the line 4—4 of Fig. 3, and

Fig. 5 is a fragmental longitudinal section somewhat enlarged of a modification.

In standard practice dial plates made out of glass are provided with a metal backing. As shown in Fig. 1, 10 designates a dial provided with calibrations 11 and numbers 12 denoting frequencies. The dial 10 is provided with transparent portions 13 and 14 in the form of slots through which the index hands are visible. A metal backing plate 15 co-extensive with the dial plate is provided with slots 16 which respectively coincide with the dial portions 13 and 14. The backing plate 15 is formed with lugs 17 and 18 which are bent over the dial plate to secure the backing plate thereto.

The dial plate and the backing are separated

by a very narrow air space so as to render the edge lighting effective.

The present invention deals with a dial plate which does not employ a metal backing but in lieu thereof employs a transparent material as a backer.

The dial plate 20 is similar to the dial plate 10 and has also the calibrations 21 and frequency numbers 22 and unpainted portions 23 and 24 in the form of slots.

A backing plate 25 of transparent material such as glass and co-extensive with the dial plate 20 is painted with an opaque color 26 but left unpainted to provide slot like transparent portions 27 co-extensive and in registry with the portions 23 and 24 of the dial plate 20.

The backing plate 25 is secured to the dial plate 20 by an appropriate cement 28 applied at the edges. When the plates 20 and 25 are thus secured together there still remain an air space 29 therebetween so that edge lighting may be effectively applied.

In Fig. 5 a modification is shown wherein the dial plate 30 and the backing plate 31 are made of a transparent plastic material and secured together by a cement 32 leaving a slight air space 33. The modification in all other respects is the same as the embodiment shown in Fig. 3.

While the drawing illustrates the invention in connection with a dial, it is understood that it may be applied whereby legends on a plate are to be illuminated by edge lighting.

Changes and modifications within the spirit and scope of the invention are included as defined in the appended claims.

I claim:

1. In an indicia plate structure of the known type having indicia markings situated in transparent areas bordered by relatively opaque areas and adapted to be illuminated by edgeglow light transmitted interiorly of the plate from an edge region thereof, improvements including the following, to wit: backing means for said first-mentioned indicia plate and comprising a second plate member mounted in closely confronting parallelism with said first plate, said second plate having transparent areas registered with the said areas on the first plate, said plates being joined and spaced apart by a slight thickness of adhesive material engaging the confronting marginal faces of said plates and leaving an air space between said confronting faces to assist in edgeglow illumination of said transparent areas.

2. A dial plate structure comprising a flat plate of substantially rigid transparent material ca-

pable of transmitting light internally by edge-wise illumination, said plate having indicia characters thereon and scalar markings situated in transparent frame areas on said plate, said characters and markings being adapted to be illuminated by edgeglow transmission internally of said plate; and a plate-backing structure consisting of a thin plastic sheet of the same size as said plate and having opaque areas defining transparent frame areas adapted to register with said transparent frame areas on the plate when the latter is backed in assembled relation with said sheet, said backing sheet being secured in registered assembly with said plate by means of a layer of cementitious material applied between the plate and sheet only in the region bordering the peripheral margins at the opposite ends thereof whereby an air space is afforded between the plate and sheet to facilitate edgeglow illumination of said characters and markings.

3. For use with a transparent dial plate having indicia characters thereon which are adapted to be illuminated by light transmitted internally of the plate from the edge regions thereof, said indicia characters including a plurality of scalar calibrations contained within a frame area surrounding the same, improvements comprising, to wit: a backing member for said plate and consisting of a sheet of thin transparent material having an opaque substance thereover except in frame areas identically registering with the frame areas on the plate, said backing sheet being secured to the dial plate in closely but finitely spaced relation thereto to afford an air space therebetween.

4. A dial plate structure for edgeglow illumi-

nation by transmission of light into an internally light-conductive plate from edge regions thereof, said structure comprising, to wit: the combination with a transparent dial plate having indicia thereon including at least a series of scalar calibration marks thereon, and a transparent frame-area surrounding said marks, said calibration marks being delineated by a material adapted to become luminously legible by light transmitted 5 interiorly of the plate, as aforesaid; together with a backing member consisting of a thin body of transparent material mounted against the back of said dial plate and having an opaque substance applied thereto throughout its major extent except for predetermined frame areas left transparent and of a size and placement to register with said frame areas on the dial plate when the backing member is assembled therewith, and means for securing said plate and backing member in assembled relation.

NATHAN PRITIKIN.
